UNITED STATES PATENT OFFICE.

WILLIAM C. REEVES, OF PORTLAND, OREGON.

COMBINED TRANSOM ADJUSTER AND LOCK.

1,180,428.

Specification of Letters Patent.

Patented Apr. 25, 1916.

Application filed May 5, 1915. Serial No. 26,051.

To all whom it may concern:

Be it known that I, WILLIAM C. REEVES, a citizen of the United States, residing at Portland, in the county of Multnomah and State of Oregon, have invented certain new and useful Improvements in Combined Transom Adjusters and Locks, of which the following is a specification.

The invention is primarily designed to provide means for operating transoms or analogous light and ventilating devices which are disposed at such a height as not to be readily or conveniently reached without requiring the person to mount a chair, ladder or like device.

The invention provides operating means which at the same time serves to secure the transom at the required adjusted position, said means being of such structural formation as to be readily and conveniently operated by a pulling action, the operating member being flexible and adapted in one position to admit of locking means coming into play for securing the transom or like part in the desired adjusted position and which when moved to another position releases the locking device, so that the transom may be closed or permitted to open to a greater extent as may be required in the adjustment thereof.

The invention, furthermore, has for its object the provision of transom operating and securing means which may be applied to a relatively narrow margin as when an end of the transom is close to a wall or other projecting part, such application not interfering in the least with the efficiency of the device or the convenience in the manipulation thereof.

With these and other objects in view, which will readily appear as the nature of the invention is better understood, the same consists in the improved construction and novel arrangement and combination of parts which will be hereinafter fully described and particularly claimed.

Referring to the drawings,—Figure 1 is a perspective view showing the application of the invention; Fig. 2 is a front view of the parts illustrated in Fig. 1; Fig. 3 is a section on the line 3—3 of Fig. 2 looking to the left, as indicated by the arrows, the full lines showing the normal position of the

operating member when the transom is fastened and the dotted lines showing an 55 adjusted position of the operating member when the locking device is released to admit of opening or closing the transom; Fig. 4 is an enlarged detail of a portion of the sprocket wheel, dog coöperating therewith and the 60 operating member for moving the dog into released position, as indicated by the dotted lines; Fig. 5 is a horizontal section on the line 5—5 of Fig. 4; Fig. 6 is a detail perspective view of the slide and the bracket 65 forming a mounting therefor; Fig. 7 is an enlarged sectional view of the shock absorbing device interposed in the length of the operating member; Fig. 8 is a detail perspective view of the dog constituting the 70 locking device which coöperates with the sprocket wheel for securing the transom or like part in the located position. Fig. 9 is an enlarged section of a portion of the 75 casing and sprocket wheel showing more clearly the manner of mounting the latter.

Corresponding and like parts are referred to in the following description and indicated in all the views of the drawings by the same reference characters.

The numeral 1 designates a transom or like part generally employed for obtaining light and ventilation over door ways and at other convenient points in dwellings and buildings generally. A bracket 2 is secured 85 to the transom or like part 1 at one end thereof and at some distance from its hinge connection with the door frame or other casing surrounding the opening in which the transom or like part is fitted. As shown 90 most clearly in Fig. 3 the transom 1 is hinged at its lower edge so as to swing outward and downward at its upper edge. The bracket 2 is formed with a vertical sleeve 3 at its outer end which constitutes a guide 95 for receiving a slide 4. A pin 5 projects laterally from the slide 4 and is arranged to operate in a vertical slot 6 formed in the outer side of the sleeve or guide 3. The pin 5 limits the movements of the slide 4 and 100 also constitutes attaching means for connecting the operating member 7 with the slide.

A casing 8 is attached to the frame or like part inclosing the opening in which the 105 transom is fitted and such casing may be of

any construction so as to provide a light and neat appearance and which may be cheaply manufactured and form a substantial housing for the sprocket wheel and co-
5 operating locking device. A sprocket wheel 9 is mounted in the casing 8 and is preferably hollow so as to receive a spiral spring 10 which is utilized to facilitate the opening of the transom. The spring 10 is connected
10 at its outer end to the outer portion of the sprocket wheel and at its inner end to one of a number of tongues 11 partly cut from a side wall of the casing and bent inwardly at a right angle and forming a support for
15 the spring 10. The sprocket wheel 9 has a hub 9^a through which a sleeve 9^b passes. This sleeve 9^b is a trifle longer than the hub 9^a to prevent binding of the sprocket wheel 9 between the sides of the casing. A fasten-
20 ing 9^c passes through the sleeve 9^b and connects the sides of the casing. The operating member 7 preferably consists of a chain, the links of which are of such shape and size as to coöperate with the teeth 12 of the
25 sprocket wheel and thereby positively rotate the same so as to place the spring 10 under tension when the transom is closed. The operating member 7 passes over the sprocket wheel thence down in the rear thereof so as
30 to lie against the door frame or like part. When the transom is closed the spring 10 is under tension and the transom is secured by means of the lock device which consists of a dog 13 arranged to engage one or an-
35 other of the teeth 12 of the sprocket wheel.

The dog 13 is provided at one end with a weight 14 and at its opposite end with a projecting tooth 15 which is adapted to engage any one of the teeth 12 of the sprocket
40 wheel, as indicated by full lines in Figs. 3 and 4, thereby holding the transom in the adjusted position. A sleeve 16 is formed with the dog as a part thereof and projects beyond opposite sides thereof and is adapt-
45 ed to receive a pin 17 upon which the dog is mounted. The weighted end 14 of the dog is made rounding to insure the ready pas-
50 sage thereover of the operating member 7. The projecting end or tooth 15 of the dog constitutes a stop to limit the movement of the dog when the same is moved by the operating member to clear the teeth of the sprocket wheel and thereby prevent any inter-
55 ference of the dog with the free movement of the sprocket wheel either in the opening or the closing of the transom. The lower wall of the casing 8 is provided with an opening for the operating member 7 to pass through and to receive a portion of the
60 dog 13. The projecting end or tooth 15 of the dog is adapted to engage the part of the casing adjacent the outer end of such opening and thereby limit the movement of the dog as indicated most clearly by the dotted
65 lines in Fig. 4.

The parts of the transom operator and fastener are disposed so that when the transom is closed the pin 5 will engage the rear portion of the sprocket wheel, as indicated most clearly in Fig. 3. In this position the 70 projecting end 15 of the dog 13 engages a tooth 12 of the sprocket wheel and holds the same against the tension of the spring 10, thereby securing the transom in locked position. When it is required to open the transom the lower end of the operating mem-
75 ber 7 is swung outward away from the door frame and is thereby brought into engage-
ment with the weighted end of the dog 13, thereby pressing the rear end of the dog 80 upward and forward with the result that the toothed end 15 of the dog is moved away from the sprocket wheel into the position shown by dotted lines in Fig. 4, thereby clearing the teeth of the sprocket wheel. 85 The operating member 7 being held in the position indicated by dotted lines in Fig. 3 and the pull thereon being relaxed to admit of the sprocket wheel 9 turning in an anti-
clockwise direction the pin 5 in engagement 90 with a tooth of the sprocket wheel is moved upward and forward thereby positively opening the transom and moving the same to such a position that it will open by its own weight after the pin 5 has cleared the 95 sprocket wheel. It will thus be understood that the spring 10 is utilized as means for positively opening the transom and moving the same past a dead point so that the transom will open by its own weight after the 100 pin 5 has cleared the sprocket wheel. When the transom has opened to the required dis-
tance it is made fast by bringing the lower portion of the operating member 7 into vertical position, thereby releasing the weighted 105 end of the dog 13. When the weighted end of the dog 13 is relieved of the pressure of the operating member 7 it drops thereby elevating the toothed end 15 of the dog and bringing the same in position to engage a 110 tooth of the sprocket wheel which latter is prevented from further rotation in an anti-
clockwise direction, thereby holding the transom in the desired position by the co-
operation of the operating member 7 and 115 teeth of the sprocket wheel. If it be re-
quired to open the transom farther the lower end of the operating member 7 is drawn out-
ward away from the door frame, thereby re-
leasing the dog by exerting an inward and 120 upward pressure upon the weighted end thereof and by permitting the operating member to move upward the transom lowers. On the other hand should it be required to close the transom the lower end of the op-
erating member is pulled upon thereby rotating the sprocket wheel in a clockwise di-
rection, the teeth 12 of the sprocket wheel 125 riding upon the toothed end 15 of the dog 13. When the transom is entirely closed the 130

pin 5 passes over the upper portion of the sprocket wheel and to a point in the rear thereof, as indicated in Fig. 3.

The operating member 7 may be provided in its length with a shock absorber or yieldable stop 18 which relieves shock in the event of the transom dropping suddenly to the limit of its opening movement. This shock absorber may be of any construction and as shown comprises a support 19 and an expansible helical spring 18. The upper end of the spring 18 is arranged to engage the casing 8 when the transom is at the limit of its opening movement. The lower end of the spring 18 engages a shoulder 20 at the lower end of the support 19. A cord or other connection 21 is attached to the lower end of the support 19 and extends within convenient reach to be pulled upon when it is required to operate the device.

Having thus described the invention, what is claimed as new is:—

1. Transom operating means comprising a toothed rotary member mounted independently of the transom, a flexible operating member connected with the transom, and positively engaging the teeth of the rotary member and a dog pivotally mounted intermediate of its ends and having one end projected into the path of the teeth of the rotary member to hold the transom in the adjusted position, the other end of the dog being disposed to be engaged by the operating member when the latter is moved from a normal position to effect release of the dog from the rotary member when it is required to adjust the transom.

2. Means for operating a transom or like part, the same consisting of a rotary toothed member mounted independently of the transom, a flexible operating member having connection with the transom and positively engaging the teeth of the rotary member, a dog arranged to engage the teeth of the rotary member to hold the transom in positions of adjustment and adapted to be released by the operating member when it is required to open the transom, means normally exerting a force to adjust the transom, and connecting means between the transom and rotary member to insure an initial movement of the transom when released preliminary to opening.

3. Operating means for a transom or like part, the same comprising a rotary toothed member, an operating member adapted to be connected with the transom and having positive engagement with the teeth of the rotary member, means for securing the transom when closed, a spring coöperating with the rotary member to impart a movement thereto in the direction of the opening of the transom, and means projecting from the transom and adapted to be engaged by

the rotary member to impart an initial movement to the transom when the same is opening.

4. Means for operating a transom or like part, the same comprising a rotary member, an operating member positively engaging the rotary member, means normally tending to turn the rotary member in a direction to cause opening movement of the transom, and means connecting the operating member with the transom and having a limited movement upon the latter to positively engage the rotary member during the final closing movement of the transom, whereby the transom is positively moved when opening.

5. Means for operating a transom or like part, the same comprising a rotary member, a slide mounted upon the transom, a pin projecting from the slide and adapted to positively engage the rotary member, an operating member connected with the slide and positively engaging the rotary member, and means for turning the rotary member to insure an initial movement of the transom toward open position.

6. Means for operating a transom or like part, the same comprising a rotary toothed member, a spring for imparting a movement to the rotary member in a direction to cause opening of the transom, means projecting from the transom and adapted to positively engage the rotary member, an operating member connected with the transom and engaging the teeth of the rotary member, and a locking device for engaging the teeth of the rotary member to hold the transom in the positions of adjustment and adapted to be released by the operating member when the latter is moved toward one position.

7. Means for operating a transom or like part, the same comprising a rotary toothed member mounted independently of the transom, means for normally tending to turn the rotary member in a direction to cause opening movement of the transom, a slide mounted upon the transom, a pin projecting from the slide and adapted to engage the teeth of the rotary member, an operating member connected with the pin and engaging the teeth of the rotary member, and a locking device disposed to engage the teeth of the rotary member to hold the transom in positions of adjustment and adapted to be released by the operating member when the latter is swung from a normal position.

8. Transom operating means comprising a rotary toothed member, a spring coöperating with the rotary member and normally tending to turn the same in a direction to cause opening movement of the transom, means movably mounted upon the transom and projecting therefrom to engage the toothed portion of the rotary member, a

flexible operating member connected with the transom and positively engaging the teeth of the rotary member to hold the transom in positions of adjustment and adapted
5 to be moved by the operating member into a position to release the rotary member when it is required to adjust the transom.

In testimony whereof I affix my signature in presence of two witnesses.
